US00D858443S

(12) **United States Design Patent** (10) **Patent No.:** **US D858,443 S**
(45) **Date of Patent:** **** Sep. 3, 2019**

(54) **CONNECTOR TERMINAL**

(71) Applicant: **Tarng Yu Enterprise co., ltd.**, New Taipei (TW)

(72) Inventors: **Mu-Jung Huang**, New Taipei (TW); **Ying-Chung Chen**, New Taipei (TW); **Chai-Fa Chang**, New Taipei (TW)

(73) Assignee: **TARNG YU ENTERPRISE CO., LTD.**, New Taipei (TW)

(**) Term: **15 Years**

(21) Appl. No.: **29/657,536**

(22) Filed: **Jul. 23, 2018**

(30) **Foreign Application Priority Data**

Jan. 29, 2018 (TW) 107300549

(51) **LOC (12) Cl.** **13-03**

(52) **U.S. Cl.**

USPC **D13/133**

(57) **CLAIM**

The ornamental design for a connector terminal, as shown and described.

DESCRIPTION

FIG. 1 is a perspective view of a connector terminal showing the new design;

FIG. 2 is a front view of a connector terminal showing the new design;

FIG. 3 is a rear view of a connector terminal showing the new design;

FIG. 4 is a left side elevational view of a connector terminal showing the new design;

FIG. 5 is a right side elevational view of a connector terminal showing the new design;

FIG. 6 is a top view of a connector terminal showing the new design;

FIG. 7 is a bottom view of a connector terminal showing the new design; and,

FIG. 8 is another perspective view of a connector terminal showing the new design.

1 Claim, 8 Drawing Sheets

UNITED STATES PATENT AND TRADEMARK OFFICE
CERTIFICATE OF CORRECTION

PATENT NO. : D858,443 S
APPLICATION NO. : 29/657536
DATED : September 3, 2019
INVENTOR(S) : Mu-Jung Huang, Ying-Chung Chen and Chia-Fa Chang

Page 1 of 1

It is certified that error appears in the above-identified patent and that said Letters Patent is hereby corrected as shown below:

On the Title Page

Item (72) Inventors should read: Mu-Jung Huang, New Taipei City (TW);
Ying-Chung Chen, New Taipei City (TW);
Chia-Fa Chang, New Taipei City (TW)

Signed and Sealed this
Thirteenth Day of December, 2022
